James Montgomery

United States Patent Office.

JAMES MONTGOMERY, OF MARSEILLES, ILLINOIS.

Letters Patent No. 103,353, dated May 24, 1870.

IMPROVED CURTAIN-FIXTURE.

The Schedule referred to in these Letters Patent and making part of the same

To all whom it may concern:

Be it known that I, JAMES MONTGOMERY, of Marseilles, in the county of LaSalle, in the State of Illinois, have invented a new and useful Improvement in Curtain-Fixtures; and I do hereby declare that the following is a full, clear, and exact description of the construction and operation of the same, reference being had to the annexed drawings making a part of this specification, in which—

Figure 1 is a vertical front view.

Figure 2 is a vertical side view.

Figure 3 is a vertical front view of the shade drawn up and the sash let down.

Figure 4 is a section through *a b*, fig. 3.

Figures 5 and 6 are plans of a detached piece.

This invention relates to an improvement in paper or cloth window-shades, of the kind that is rolled up and down from a wooden mandrel fastened to the lower end, while the top bar has been heretofore fastened to the casing of the window, and consists in the combination and arrangement of parts, as hereinafter more fully described.

My improvement is attached to any ordinary window, consisting of the casing A, the lower sash B, and the upper sash, B'.

To the upper sash B' I attach the top bar C, by means of two springs D D, in such manner that the springs will cause the bar C to press against the casing A with sufficient force to support the weight of the sash B' and of the shade E attached to the bar C. This will be sufficient under ordinary circumstances, while for very large sashes, or where safety is required,

a separate sash lock may be used, in which case the top bar C need not press against the casing A.

The shade E is of any of the patterns usually made, and is rolled up on a stick or mandrel.

To roll it up and down I employ two cords F F, fastened to the top bar C; thence the cords F F pass down under the shade E, and up through two staples, G G; thence through a central staple H, thence down again, and, finally, unite in a tassel, J, which contains hidden inside a piece of lead, K, of sufficient weight to prevent the shade E from unrolling itself, a very small weight being required for that purpose, on account of the friction of the cords F F in the staples G G and H.

I do not claim as my invention the several devices already covered by the following United States Patents: George P. Fuller, September 28, 1869; E. B. Lake, July 23, 1869; J. B. Moore, March 10, 1868; C. C. Matchett, March 3, 1868; A. M. Cheney, April 20, 1869; and J. M. Burns, January 25, 1870.

What I claim as my invention, and desire to secure by Letters Patent, is—

The combination of the devices above named, so as to form the window-shade as described, that is to say, of the top bar C, the springs D D, the cords F F, the staples G G, the staple H, weighted tassel I, and shade E, in combination with the window-sash B', constructed substantially as described.

JAMES MONTGOMERY.
